UNITED STATES PATENT OFFICE.

JULES ISTAS, OF BRUSSELS, BELGIUM.

CURRENT-INTERRUPTING DEVICE FOR ELECTRICALLY-HEATED WATER-DISTRIBUTING APPARATUS.

Application filed December 27, 1923. Serial No. 683,064.

To all whom it may concern:

Be it known that I, JULES ISTAS, a citizen of the Kingdom of Belgium, and resident of Brussels, Belgium, have invented certain new and useful Improvements in or Relating to a Current-Interrupting Device for Electrically-Heated Water-Distributing Apparatus; and I do hereby declare the following to be a full, clear, and exact description of the invention, such as will enable others skilled in the art to which it appertains to make and use the same, reference being had to the accompanying drawings, and to letters or figures of reference marked therein, which form a part of this specification.

The present invention has for its object a current interrupting device for electrically heated water distributing apparatus, characterized by the fact that it is constituted by a piston integral with the movable part of a current interrupter and adapted to be displaced in a cylinder provided with a water inlet pipe and with a water outlet pipe, the former being situated below the piston in its position of rest, and the other above, the said piston being moved in one direction by the pressure of water and in the other direction by a return arrangement, and being provided with a small conduit establishing connection between its two faces.

The annexed drawing represents by way of example two embodiments of an interrupter device according to this invention.

Figure 1 represents the application to a distributing arrangement for hot water under pressure,

Figure 2 the application to a distributing device for hot water with free outflow.

In the interior of a cylinder a , provided at its lower portion with a water inlet pipe a^1 and near its upper portion with a water outlet pipe a^2 , is adapted to move a piston b integral with a rod b^1 , traversing the cylinder a through a stuffing box c . A passage b^2 of small cross section is arranged in the piston b to establish communication between the two faces of the piston and a spring b^3 arranged around the rod b^1 and supported on the one hand on the cylinder a and on the other hand on the piston b tends con-

stantly to return the piston b to the position represented in the figures of the drawings.

55

Secured to the rod b^1 of the piston is the movable part d of an interrupter, the fixed part of which is represented at d^1 .

In series with the conduit e for the incoming water, which is connected to the pipe a^1 of the cylinder a , is arranged a heating coil f , the heating of which is obtained by resistances g located between its turns; the water, after having circulated in the coil f , the conduit e and the cylinder a , flows out by way of a conduit h connected to the pipe a^2 of the cylinder a and provided with a stopcock i . The resistances g are connected to the source of current through the interrupting device d , d^1 .

70

In the example illustrated in Figure 2 the cock i , instead of being arranged in the water outlet conduit h , is provided on the water inlet conduit e and in front of the heating coil.

75

The operation of this arrangement is as follows:

The cock i being closed, the parts occupy the position represented in the drawing. When the cock i is opened, the equilibrium between the two faces of the piston being disturbed, the pressure of the water moves the piston b until it uncovers the orifice a^2 ; the stroke of the piston b is so chosen that the interrupter d , d^1 is closed at this moment, whereby the resistances g are placed in circuit, and the water traversing the coil is heated. When the cock i is closed, the piston b descends under the action of the spring b^3 , at the same time opening the interrupter d , d^1 ; and this descending movement is rendered possible due the presence of the passage b^2 which allows the flow of water from one face of the piston to the other.

85

It is evident that the invention is not limited to the details of the construction hereinbefore described, and that it may be carried out according to other modifications based on the same principle. Thus, for instance, the construction could be arranged for the interruption of direct current, or single phase or polyphase alternating current.

95

100

What I claim is:

A current interrupting device for electrically heating water in a water distributing apparatus, comprising a piston integral with the movable member of the current interrupter, said piston being adapted to be displaced in a cylinder, an inlet pipe on said cylinder below the piston in its position of rest and a water outlet pipe above, the said piston being moved in one direction by the

pressure of the water and in the other direction by a return arrangement, and being provided with a narrow conduit establishing communication between its two faces.

In testimony whereof I affix my signature ¹⁵ in presence of two witnesses.

JULES ISTAS.
